(57) **CLAIM**

The ornamental design for a barrel cleaning device, as shown and described.

DESCRIPTION

FIG. 1 shows a perspective view of a barrel cleaning device. FIG. 2 shows a right side view of the barrel cleaning device. FIG. 3 shows a left side view of the barrel cleaning device. FIG. 4 shows a bottom plan view of the barrel cleaning device.

FIG. 5 shows a top plan view of the barrel cleaning device. FIG. 6 shows a front view of the barrel cleaning device. FIG. 7 shows a rear view of the barrel cleaning device.

FIG. 8 shows a perspective view showing the design in an environment of use; and,

FIG. 9 shows a perspective view showing the design in an environment of use.

The broken lines in FIG. 8 and FIG. 9 depict environmental features that form no part of the claimed design.

1 Claim, 5 Drawing Sheets
